UNITED STATES PATENT OFFICE.

SAMUEL GUTHRIE, OF SAN FRANCISCO, CALIFORNIA.

AIR-COMPRESSOR.

SPECIFICATION forming part of Letters Patent No. 417,482, dated December 17, 1889.

Application filed December 12, 1888. Serial No. 293,369. (No model.)

To all whom it may concern:

Be it known that I, SAMUEL GUTHRIE, of the city and county of San Francisco, State of California, have invented an Improvement 5 in Air-Compressors; and I hereby declare the following to be a full, clear, and exact description of the same.

My invention relates to an automatic apparatus for compressing air; and it consists 10 in a combination of mechanism which will be more fully explained by reference to the accompanying drawings, in which—

Figure 1 is a longitudinal vertical section of my apparatus. Fig. 2 is an end view of 15 my apparatus.

The object of my invention is to employ a column of water under pressure to compress air from a compressing-chamber into a receiver, the water being alternately admitted 20 to and discharged from the chamber, so that when it is admitted it will force a body of air from this chamber into a receiver, and when discharged another body of air will be admitted to be again compressed, the operation 25 being conducted automatically by the action of filling and discharging.

A and B are two chambers, one serving as a compressor and the other as a receiver. In the present case I have shown these chambers 30 in the form of horizontal cylinders lying side by side; but it will be manifest that any other suitable or convenient form of chamber may be employed. In the chamber A, I have shown an extension C from the lower part, 35 into one side of which the supply-pipe D enters. This supply-pipe connects with a chamber having a balanced valve E, of any usual or suitable construction, through which the water may pass from the pipe into the 40 chamber; when the valve is opened, until the chamber A is filled. Within the same extension C, as at present shown, is another balanced valve F, connecting with a discharge-pipe G, through which, when the valve F is 45 opened, the water may be discharged from the chamber A. These valves have the stems H and I, which pass up through the top of the chamber A and are connected with a lever J at points equidistant from the fulcrum 50 K, so that when the lever is moved to open one valve it will close the other, and vice versa. In order to open and close these valves,

I employ a float L, which rises and falls within the chamber A, having suitable guides to keep it in line. With the present construction I have shown the chamber A provided with extensions above and below, as shown at M, these extensions being of sufficient diameter to allow the float L to pass into them while it is at its lowest and highest points; 55 but it will be manifest that if the chamber A were elongated vertically it would not be necessary to make these additional extensions.

N is a rod extending up through the top of 60 the upper chamber M and passing down through the center of the float L. Upon the upper end of this rod is a device for the operation of the valve-lever J. It consists of a diamond-shaped piece O, attached to the rod 65 N and having projections or lugs P at points above and below the end of the lever J, (which is extended upon this side, so as to pass across the face of the diamond-shaped piece O and between the lugs P P.)

Q Q are two lever-arms fulcrumed upon a supporting-frame at R, depending therefrom, and having upon the lower ends anti-friction wheels or rollers S, which travel in contact with the opposite inclined edges of the diamond plate O. These levers are provided 80 with weights, as shown at W, or with equivalent springs, which cause the lower ends to close or draw together with considerable force. It will be manifest that when these 85 rollers S S are pressing upon the inclined edges of the plate O, either above or below the widest point of the plate, they will cause the plate to slide up or down, as the case may be, and by means of the pins P will move the 90 lever J, and thus actuate the valves E and F through their connecting-rods H and I.

The operation will then be as follows: The chamber A being empty, the float L will be at its lowest point, and the upper pin P on the 95 plate O, which is attached to the rod N, will have engaged the lever J, and forced it down, so as to open the inlet-valve E and close the outlet-valve F. Water from the pipe D will then flow into the chamber A from the valve 100 E, and as the chamber fills will gradually raise the float L until the upper portion of the float comes in contact with the collar T, which is fixed upon the rod N. This will oc-

our while the float is still a short distance from its highest point, and the subsequent upward movement of the float will move the rod N upward, carrying with it the plate O. The edges of the plate moving between the the rollers S will separate them until they have passed the angles of the plate which are widest apart horizontally, the distance between the pins P P allowing of this movement without moving the levers J or the valves. As soon as the rollers S have passed the angles of the plate O and are upon the inclined lower edges of the plate the action of the weight or spring tending to close the lower ends of the lever together will by this action move the plate O suddenly upward, carrying with it the rod N, and the lower pin P, being then in contact with the lever J, will act so as to suddenly reverse the valves E and F, closing the inlet-valve and opening the outlet-valve. The air with which the chamber A was filled before the water was admitted will be forced out by the pressure of the incoming water passing through the check-valve at U and upward through the pipe V, passing over into the air-chamber B, where it will be compressed to a degree corresponding with the head or pressure of water which is admitted into the compressing-chamber A. As soon as the valves E and F are reversed by the action previously described the water will commence to flow out of the escape-pipe G and the float L will again move downward until it engages with another collar T' upon the lower part of the rod N, when the rollers S will again be spread by the downward movement of the plate O, and the sudden action and reversal of the valves will take place when the float has reached the bottom by the pressure of the rollers upon the upper inclined sides of the plate O, which will again reverse the valves. As soon as the water commences to escape from the chamber A the check-valve U in the pipe V will close, so as to prevent any escape of air from the chamber B. At the same time the valve at W' will be opened to admit another charge of air to the chamber A. In this manner I am enabled to automatically compress air into large or small quantities and to any degree, limited only by the pressure of the column of water which is supplied to the compressing-chamber A.

Having thus described my invention, what I

claim as new, and desire to secure by Letters Patent, is—

1. The chamber A, with a rising and falling float, the air-supply, and the water inlet and outlet valves, with the corresponding supply and discharge pipes, a fulcrumed lever connected with said valves, so that the movement of the lever opens one valve and closes the other simultaneously, in combination with a rod the upward or downward motion of which is commenced by the rising and falling of the float, a cam-plate O, fixed to said rod, and weighted arms Q, pressing upon the edges of the cam-plate, so that when the widest portion of the plate has passed between them the final movement will be completed suddenly by the action of the arms upon the inclined sides of the plate, and pins or connections whereby the valve-operating mechanism will be moved at the same time, substantially as herein described.

2. A chamber A, with air inlet and outlet valves in the upper part, a receiver with which the air-outlet is connected, water inlet and outlet valves in the lower part, with supply and discharge pipes connected therewith, an oscillating lever with which said valves are connected, a vertical sliding rod having pins fixed to it above and below the end of the oscillating lever, so as to engage the stem, and a diamond-shaped cam-plate fixed to and movable with the rod, in combination with a rising and falling float within the chamber A, collars fixed to the vertical rod N so as to be engaged by the float before reaching its highest or lowest point, and weighted lever-arms Q, so fulcrumed that their lower ends press upon the edges of the cam-plate and are spread by the upward or downward movement of the rod N and cam-plate until they pass the widest portion of the cam, after which the pressure of the levers completes the movement of the rod and cam-plate and by the action of the pins on the cam-plate or its rod moves the oscillating lever and reverses the position of the water-valves, substantially as herein described.

In witness whereof I have hereunto set my hand.

SAML. GUTHRIE.
